UNITED STATES PATENT OFFICE.

WILLIAM SCHMITT, OF NEW YORK, N. Y.

CONVERTIBLE CHAIR.

Application filed November 10, 1923. Serial No. 674,054.

To all whom it may concern:

Be it known that I, WILLIAM SCHMITT, a citizen of the United States, and a resident of the city of New York, borough of Manhattan, in the county and State of New York, have invented a new and Improved Convertible Chair, of which the following is a full, clear, and exact description.

This invention relates to a convertible chair, and has for an object the provision of a simple, durable, efficient and compact construction of chair which will permit it to be expanded so as to form a bed or a divan.

Another object concerns the provision of means whereby the operation and manipulation of the bed is rendered extremely simple, so that any one without any particular amount of strength can expand and contract the chair.

A further object concerns the provision of means whereby the chair when expanded is, nevertheless, capable of supporting proper load without distortion and breaking.

A still further object concerns the provision of means whereby in opening the chair and in closing it only a very few manipulations thereof are required.

The invention is illustrated in the drawings, of which—

Figure 1 is a perspective view of the chair in its contracted position;

Fig. 2 is a perspective view showing the chair partly expanded;

Fig. 3 is a perspective view showing the chair fully expanded in the form of a bed;

Fig. 4 is an elevation of part of the bed and part of the chair showing the particular manner in which the supporting frames interact;

Fig. 5 is a section through the chair showing the way in which slidably interengaging sections are connected;

Fig. 6 is a plan view showing a detail of the interengagement of the slidable sections;

Fig. 7 is a plan view of a modified form; and

Fig. 8 is a section taken on the line 8—8 of Fig. 7.

The form of the invention shown in the drawings is a preferred form, although it is understood that modifications in the construction and arrangement of the parts and in the character of the materials used may be

adopted without departing from the spirit 55 of the invention as set forth in the appended claims.

In general, the chair when used as a chair has the appearance of an ordinary arm chair having a pivoted back capable of being adjusted at the proper inclination. The chair, however, is provided with side frames which are connected by a plurality of slidably interengaging elements, such as bars, to one of which slidable sections or bars the pivoted back is connected. The slidable engagement of the bars or sections permits the side frames to be pulled away from each other to increase the distance therebetween. This expansion, by reason of the telescopic 70 action of the slidable sections, permits the frames to be pulled out sufficiently far to make a full length bed, if necessary. The chair is also provided with a plurality of load engaging frames which, by their interaction, will cover the slidable sections as the chair is expanded to form a complete load engaging frame. The pivoted back is adapted, when the chair is expanded, to act as one of the load engaging frames as it is folded 75 down into the proper position.

As shown in the drawings, which discloses the preferred embodiment of my invention, the chair comprises side frames 1 and 2, of any usual type, which are connected by a 85 plurality of interlocking slidable sections such as 3, 4, 5, 6 and 7 and 3^a, 4^a, 5^a, 6^a and 7^a. These sections, as will be seen from a consideration of the drawings, are arranged in pairs at the front and rear of the side frames 90 1 and 2. As shown in Fig. 5, from a consideration of which the interlocking action will be clear, each section engages with its adjacent section by reason of the fact that one section is provided with a lip, such as 8, 95 and there is provided on the adjacent section a groove 9 into which the rib projects.

As shown in Fig. 6, the top of one section may be provided with a depressed portion such as 10 in which a plate such as 11 is fastened by any suitable means. The outer end of this plate extends over the adjacent section and is bent down and is adapted to slide in a groove 12 in this adjacent section. This interengagement, therefore, permits the 100 slidable movement of the sections longitudinally relative to each other, the rib and groove construction preventing any relative

vertical movement, and the plate and groove construction preventing any relative lateral movement. In other words, these sections can only move relatively to each other in a direction to expand or increase their total length or decrease said length. It is understood, of course, that the inner ends of the inner pair of sections are connected to one of the side frames 1 and 2, and the ends of the other pair of end sections are connected to the other side frame.

As shown in Figs. 7 and 8, it may be advisable where the expanded length of the chair is more than a certain amount to provide a cross strut, such as 13, which on its ends may be connected to the underside of a pair of the slidable sections, such as 5 and 5^a, as shown in Fig. 8.

The chair is provided with a back frame 14 which, as shown in Figs. 1 and 5 particularly, is hinged to the section 3^a, and when the chair has been expanded to the position shown in Fig. 2 it can be folded down across the sections 3 and 3^a into the position shown in Fig. 3 to form a load engaging frame. The chair is also provided with a load engaging frame such as 15 which is fastened in any suitable manner to the slidable sections 5 and 5^a, as shown in Figs. 3 and 4. The chair is also provided with a third load engaging front 16 which at its outer end is loosely connected, as shown in Fig. 4, to the side frame of the chair. This last engagement is effected by the provision of a pair of hook members such as 17 on the under end surface of the frame 16 which engages with a pair of bails such as 18 disposed on the side frame 1 of the chair. This last engagement holds the frame 16 to the side frame but permits it to be elevated.

As shown in Fig. 4, the chair has been expanded to its full length so that the frame 16 lies on top and across the slidable sections 7 and 7^a and also partly across the sections 5 and 6 and 5^a and 6^a. However, when the operation of contracting the chair takes place, the side frame 1 is forced inwardly toward the frame 2, and when this happens it will be noted that the frame 16 will ride up, as shown in dotted lines in Fig. 4, on the frame 15 because the ends 19 and 20 of these frames are tapered to permit this action to take place. By reason of the fact that the other end of the frame 16 is loosely connected to permit it to be elevated as the further contraction of the chair takes place, the frame 16 will ultimately rest on top of the frame 15, as shown in Fig. 2, so that the frame 16 will directly contact with the load.

In the position of the parts shown in Fig. 2, therefore, the chair is expanded to form a sort of divan long enough to permit two or three people to sit on it. In this case the back frame 14 is folded down across the

frame 3 and 3^a. By pulling the chair out further, to the position shown in Fig. 3, then the three load engaging frames 14, 15 and 16 each occupy a proper position across the slidable section adjacent each other to form a full-length bed. It will also be noted that the top edges of the frame 15 are provided with strips, such as 21, of any suitable material such as metal of a desired thickness, so that when the frame 16 meets the frame 15 the contact will be mainly between the edges of the frame, so that the upholstery or other fabric comprising the major portion of the surface of these frames will not bear and rub too strongly against each other, thus preventing wear.

It will thus be apparent that I have provided a simple, durable and compact apparatus which in its normal condition will act as an arm chair with a tiltable back which, by the usual adjusting means 22 shown in Fig. 1, can be disposed at any desired angle. It will also be apparent that this chair can be pulled out to any desired degree to form a divan or full-length bed and that the transformation of the chair into a bed can be effected in a very simple manner and with very few operations. It is also apparent that the bed is capable of supporting the proper load without derangement even when fully extended.

What I claim is:—

1. A convertible chair and bed comprising a pair of side frames designed to constitute the sides of a chair in the chair-forming position, of the parts and the head and foot of the bed in the bed-forming position of the parts, a plurality of front sections extending transversely between the side frames at the front, a plurality of back sections extending transversely between the side frames at the back, the front sections having interfitting means whereby the front sections are slidably interengaged with each other, certain of the front sections being connected with the side frames, the back sections having interfitting means whereby the back sections are slidably interfitted with each other, certain of the back sections being also connected to the side frames, the front sections and the back sections constituting the front and back of the chair when the parts are in chair-forming position and constituting the side rails of the bed when the parts are in bed-forming position, the front and back sections being located in the same plane and on the same level throughout their extent and being spaced at approximately the same distance throughout their extent and being symmetrically disposed with respect to the longitudinal axis of the bed to provide a bed of approximately uniform width, and load-engaging frames co-operable with the sections to complete the bed bottom in the bed-forming po- 125

sition and also co-operable with the sections to form the seat and back of the chair in the chair-forming position.

2. A convertible bed which comprises a pair of side frames connected by a plurality of slidably engageable sections, a load engaging frame fixed to a pair of said sections and slidable therewith, a load engaging frame loosely engageable with one of said side frames and adapted when the apparatus is in its contracted position to lie over

said previously mentioned load engaging frame and adapted when the apparatus is expanded to form a bed to be disposed on the slidably engageable sections independently of said previously mentioned load engaging frame, and a pivoted back frame to said chair adapted when the chair is expanded to form a bed to fold down on certain of said slidably engageable sections to form another load engaging frame. 15 20

WILLIAM SCHMITT.
